UNITED STATES PATENT OFFICE.

GEORGE W. ANGELL, OF GRAND RAPIDS, MICHIGAN.

ADJUSTABLE TABLE.

1,091,615.

Specification of Letters Patent. Patented Mar. 31, 1914.

Application filed February 23, 1912. Serial No. 879,581.

To all whom it may concern:

Be it known that I, GEORGE W. ANGELL, a citizen of the United States, residing at the city of Grand Rapids, in the county of Kent 5 and State of Michigan, have invented a new and useful Adjustable Table, of which the following is a specification.

My invention relates to improvements in adjustable tables and more particularly to 10 such tables that are vertically adjustable and its object is to provide improved means for raising and lowering the top of the table and holding the same in adjusted position and it consists essentially of the combination 15 and arrangement hereinafter more fully described and particularly pointed out in the claim, reference being had to the accompanying drawings, in which:

Figure 1 is a side elevation of a device 20 embodying my invention the table top being omitted as forming no part of my invention; Fig. 2 is an enlarged detail of a portion of the device shown in Fig. 1 with the top support somewhat elevated; Fig. 3 is a horizontal sectional detail taken through the axis of one of the elevating gears; Fig. 4 is a front elevation of the device in the position shown in Fig. 1; Fig. 5 is a detail in elevation showing the gearing at one side of the table; 30 and Fig. 6 is an enlarged vertical section through the axis of one of the gears shown in Fig. 5.

Like numbers refer to like parts in all of the figures.

35 The main frame of the table is preferably made of steel tubing and comprises four legs at the respective corners of the frame open at the top and connected by horizontal tie members 2 secured to the same thus forming 40 a substantially rectangular frame preferably mounted on casters 3. The lower ends of the legs are preferably curved outward to increase the width of the base of the device.

In each leg is a vertically slideable post 45 formed of tubing flattened on one side to receive a rack 6 or preferably a solid round steel bar with a rack cut therein. These posts are connected near the top by horizontal member 5 preferably of tubing rigidly 50 secured thereto and are adapted to support any convenient table top (not shown).

Extending across the main frame at opposite sides and secured at the ends to opposite legs are housings 14 preferably of stamped 55 sheet metal made in two equal parts and se-

cured to each other by suitable fastenings 15 surrounded by tubular sleeves 16 to space apart the housings in parallel planes each part of the housing having inwardly turned edges whereby the contents of the housing 60 are inclosed therein, and concave ends clamping the legs. To further secure the housings and legs to each other lugs 17 are secured to the legs, extend within the housings and the end fastenings 15 extend 65 through the same. The housings thus form a part of the main frame and also furnish bearings for the journals of the gears and shaft.

Across the frame from side to side and 70 journaled in these housings is a shaft 11 provided with a crank 7 for manually rotating the same. On this shaft and within each housing is fixed a pinion 8 which oppositely engages gears 9 one of which gears projects 75 through an opening in the side of a leg and engages the rack 6 therein. The other gear transmits motion to a similar gear which engages the rack in the leg at the opposite end of the housing each gear being mounted on a 80 shaft 13 journaled in the housing, each housing thus contains a train of gears operated by a pinion on the shaft and the end gears of the train adapted to move the racks simultaneously and in the same direction as occasion 85 may require by manually operating the crank 7. The two trains of gears operated thus by a single shaft simultaneously raise and lower all four of the posts equally.

To hold the device in adjusted position a 90 pawl 12 is provided in each housing to engage one of the gears 9 and hold the same from rotating.

From the foregoing description the operation of my device is obvious without further 95 explanation.

What I claim is:—

An adjustable table comprising a frame having four tubular legs spaced apart in pairs with each leg provided with an opening below its upper end, a post movable vertically in each leg, a rack on each post, connecting members between the posts, a housing bracing each pair of legs and covering the openings in the legs, a train of gears 100 journaled in each housing with the end gears of each train projecting through the corresponding openings in the legs and meshing with the racks and corresponding posts, a 105 rotatable shaft journaled in the opposite 110

housings and provided with spaced pinions for mesh with the corresponding trains of gears each operated simultaneously and said posts raised or lowered according to the direction of rotation of said shaft, and a dog pivotally mounted in each housing for engagement with a gear of each corresponding

train to prevent accidental operation of the gear trains.

GEORGE W. ANGELL.
